FIG. 1 is a perspective view of a motorcycle fender showing my new design;

FIG. 2 is a side elevational view thereof;

FIG. 3 is a bottom plan view thereof;

FIG. 4 is a top plan view thereof;

FIG. 5 is an end elevational view thereof;

FIG. 6 is a perspective view of a motorcycle fender showing a second embodiment of my new design;

FIG. 7 is a side elevational view of FIG. 6;

FIG. 8 is a bottom plan view of FIG. 6;

FIG. 9 is a top plan view of FIG. 6; and

FIG. 10 is an end elevational view of FIG. 6.

The characteristic feature of my design resides in the increasing radius of curvature from the midpoint of the fender to the substantially flat outer ends.

This application is a continuation-in-part of application Ser. No. 316,653, filed Dec. 20, 1972, and now abandoned, and a continuation-in-part of application Ser. No. 378,258, filed July 11, 1973, and now abandoned.

I claim:
The ornamental design for a motorcycle fender, as shown and described.
